CLAIM

The ornamental design for a shoulder immobilizer pillow, as shown and described.

DESCRIPTION

FIG. 1 is a front elevation view of a shoulder immobilizer pillow, a rear elevation view of the pillow being a mirror version thereof, wherein the left side of the figure represents the inner side of the shoulder immobilizer pillow and the right side of the figure represents the outer side of the shoulder immobilizer pillow when the shoulder immobilizer pillow is worn by a user;

FIG. 2 is a front perspective view thereof;

FIG. 3 is a top view thereof;

FIG. 4 is a bottom view thereof;

FIG. 5 is a side elevation view thereof; and,

FIG. 6 is a side elevation view of the opposite side thereof. The portions of the shoulder immobilizer pillow shown in broken lines form no part of the claimed design.
